(57) **CLAIM**

The ornamental design for a toiletry bag, as shown and described.

DESCRIPTION

FIG. 1 is a perspective view of a first embodiment of a toiletry bag showing my new design, shown in an open state; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the toiletry bag where the toiletry bag is in a closed state; FIG. 10 is an enlarged view of portion 10 shown in FIG. 1; FIG. 11 is a perspective view of a second embodiment of the toiletry bag shown in an open state; FIG. 12 is another perspective view thereof; FIG. 13 is a front elevational view thereof; FIG. 14 is a rear elevational view thereof; FIG. 15 is a left side elevational view thereof; FIG. 16 is a right side elevational view thereof; FIG. 17 is a top plan view thereof; FIG. 18 is a bottom plan view thereof; FIG. 19 is a perspective view of the toiletry bag where the toiletry bag is in a second open state; FIG. 20 is a perspective view of the toiletry bag where the toiletry bag is in a closed state; and, FIG. 21 is an enlarged view of portion 21 shown in FIG. 11. The dash-dash broken lines in the drawings depict portions of the toiletry bag that form no part of the claimed design. The dot-dash broken lines represent boundaries of the enlarged portions and form no part of the claimed design.

1 Claim, 21 Drawing Sheets
